UNITED STATES PATENT OFFICE.

WILLIAM REID, OF CHICAGO, ILLINOIS, ASSIGNOR TO ARTHUR L. PAYTON, OF CHICAGO, ILLINOIS.

CARBURETER.

1,283,302.

Specification of Letters Patent.

Patented Oct. 29, 1918.

Application filed February 26, 1916. Serial No. 30,572.

To all whom it may concern:

Be it known that I, WILLIAM REID, a citizen of the United States, residing at Chicago, in the county of Cook and State of Illinois, have invented a certain new and useful Improvement in Carbureters, of which the following is a full, clear, concise and exact description, reference being had to the accompanying drawing, forming a part of 10 this specification.

My invention relates to carbureters and has for its object the provision of means for automatically lifting or forcing fuel from a fuel reservoir to the fuel chamber of the 15 carbureter when the fuel reservoir is located below the normal fuel level of the carbureter.

In carrying out this object I contemplate the provision of means for utilizing the suction produced by the internal combustion 20 engine with which the carbureter is associated to provide a vacuum or reduction of pressure above fuel in the fuel chamber of the carbureter, so that I obtain a difference of pressures between the fuel located in the 25 carbureter and the fuel located in the supply reservoir. The supply reservoir contains a vent opening which subjects the fuel contained therein to atmospheric pressure whereby the fuel is forced from the supply 30 reservoir up into the fuel chamber of the carbureter. By my invention the carbureter need not be drilled, bored or in any other way mutilated or changed to produce this reduction of pressure within the fuel chamber 35 thereof.

These and other features of my invention will be more fully pointed out in connection with the accompanying drawing, which illustrates the device of my invention.

40 In the drawing, 1 illustrates a carbureter of any design connected by means of the flange usually provided thereon to the intake manifold 2 leading to the cylinders of the internal combustion engine. The carbureter is provided with the usual fuel chamber 3 and main air intake opening 4. The drawing illustrates a carbureter provided with a second air intake opening 5, commonly known as the auxiliary air intake 45 port. Positioned around the carbureter is a casing or housing 6 which is preferably held between the flange of the carbureter and the flange of the intake manifold, as illustrated. 50 This housing may be made with a glass front door 7, which is hinged at 8 to the

base of the housing, the catches 9—9 serving to hold the door in closed position. The casing 6 is preferably made substantially air tight, so that it allows substantially no air to enter it, except through an intake opening 10 provided in one of the walls of the housing. The throttle valve of the carbureter may be controlled by means of the wire 11 extending through the wall of the housing, or the shaft upon which the throttle valve is mounted may extend through the rear wall of the housing and be there connected with a wire similar to the one illustrated at 11. Similarly the valve for controlling the intake port 4 is controlled by means extending 15 through the housing. The fuel or float chamber 3 receives its supply of fuel through the conduit 12, terminating at one end in the base of the fuel supply reservoir 13. This reservoir is open to atmospheric pressure, as illustrated, so that when a reduction of pressure is produced within the fuel or float chamber of the carbureter, fuel will be forced upwardly through the conduit 12 and into the carbureter. As is well known, the 20 interior of the fuel chamber 3 of all standard carbureters is open to atmospheric pressure, so that the fuel contained therein is permitted to flow freely to the nozzle. When, therefore, a housing surrounds the carbureter, as shown, the fuel chamber is subjected only to the pressure within the housing.

The intake air opening 10 of the housing is controlled by means of an automatic valve 14, which is normally held closed by means 25 of the spring 15. It is this spring 15 which determines the amount of vacuum or reduction of pressure which is to be produced within the housing during the operation of the carbureter.

If it is desired to have a one pound reduction of pressure within the housing during the operation of the carbureter, the spring 15 is made so that the valve 14 is opened when there is produced within the housing a 30 pressure which is one pound less than atmospheric pressure. The interior of the fuel chamber 3 will then be subjected to a pressure which is one pound less than atmospheric pressure, with the result that if the conduit 12 has free communication with the fuel chamber the fuel will be forced upwardly into the same.

If desired, the intake opening 10 may be connected with a conduit 16 terminating at 35

its other end adjacent the exhaust manifold of the engine or some other source of heat, so that warm air is taken in by it. This warm air will, due to the housing, circulate around the carbureter and thus warm the fuel before vaporizing it.

I have illustrated the housing 6 as being fixed between the flanges of the carbureter and the intake manifold, but it will be readily understood that the housing may be clamped to the manifold above the flanges if the carbureter contains any mechanism which projects above the flanges.

Although I have illustrated the entire carbureter as being enveloped by the casing, I wish it to be understood that to produce the desired reduction of pressure it is necessary only to provide a housing around the intake port of the carbureter which has its interior communicating with the interior of the fuel chamber. In other words, it is not necessary to cover the entire carbureter up, although this has its advantages in that the housing can be cheaply made and that the entire carbureter is subjected to the warm air fed to it through the conduit 16.

Having thus described my invention, what I claim as new and desire to secure by United States Letters Patent is:

30 1. The combination with a carbureter hav-

ing a fuel chamber and an air inlet port, of a casing surrounding said carbureter and having an air intake opening provided with an inwardly opening spring controlled valve, a fuel supply reservoir open to the atmosphere and positioned below said carbureter, and a conduit for conducting fuel from said fuel supply reservoir to said fuel chamber. 35

2. The combination with a carbureter having a fuel chamber and an air inlet port, of a casing surrounding said carbureter and having an air intake opening provided with an inwardly opening valve, a fuel supply reservoir open to the atmosphere, and a conduit for conducting fuel from said fuel supply reservoir to said fuel chamber. 40

3. The combination with a carbureter having an air inlet port, of a casing surrounding said carbureter and having a restricted air intake port, a fuel supply reservoir opening to the atmosphere, and means for conducting fuel from said reservoir to said carbureter. 45

In witness whereof I hereunto subscribe my name this 23rd day of February, A. D. 1916.

WILLIAM REID.
